ABSTRACT: Manufacture of new antibiotic substances by the cultivation of a micro-organism belonging to *Streptomyces kitasatoensis*. The antibiotic of the invention has the general structural formula:

wherein when R₁ represents hydrogen, R₂ represents acetyl, propionyl, butyryl or where when R₁ represents acetyl, R₂ represents acetyl, propionyl, butyryl or isovaleryl.

ANTIBIOTIC PRODUCTION USING

This application is a divisional application of Application Ser. No. 655,059 filed Sept. 1, 1967, now U.S. Pat. No. 3,535,309 of Oct. 20, 1970.

This invention relates to new antibiotic agents and further to a process for preparing the same. More particularly, it is concerned with a novel antibiotic substance as expressed generally by:

wherein R_1 represents hydrogen and R_2 represents acetyl, propionyl, butyryl; or wherein R_1 represents acetyl and R_2 represents acetyl, propionyl, butyryl and isovaleryl.

The antibiotic substance called leucomycin is a kind of macrolide antibiotic which was prepared in 1953 from the cultured broth of *Streptomyces kitasatoensis*. The physical and chemical properties and biological particulars of the said leucomycin were disclosed in "JOURNAL OF ANTIBIOTICS, SER. A," Vol. VI, No. 2, p. 87-89. The taxonomical properties of *Streptomyces kitasatoensis* were disclosed in the same JOURNAL, 1953, Vol VI, No. 3, p. 109-112. These properties and particulars were also disclosed in Japanese Pat. Publication No. 2299/1955, later matured in Japanese Pat. No. 214984.

Several of us investigated into the antibiotic leucomycin and found that it can be divided generally into two groups, or more particularly into leucomycin A-group and leucomycin B-group and further that the former comprises two kinds of substances: leucomycin A_1 and A_2 , and the latter comprises leucomycin B_1 , B_2 , B_3 , and B_4 , as disclosed in Japanese Pat. Publication Nos. 18750/1960 and 98/1961 which were matured later in Japanese Pat. Nos. 278,546 and 278,547, respectively.

It is the main object of the present invention to provide several new effective antibiotics different from those denoted above leucomycin A, B, A_1 , A_2 , B_1 , B_2 , B_3 and B_4 , and called A_3 , A_4 , A_5 , A_6 , A_7 , A_8 and A_9 compounds briefly denoted throughout the present specification and particularly and definitely pointed out by the general formula disclosed hereinbefore.

Furthermore, this present invention provides a novel process for the preparation and isolation of these new antibiotics, leucomycin A_3 , A_4 , A_5 , A_6 , A_7 , A_8 and A_9 , or mixtures of these new antibiotics, although *Streptomyces kitasatoensis* is used as before as the antibiotic-producing micro-organism.

The new antibiotic agents described hereinbefore are formed during the cultivation under carefully controlled conditions by the micro-organisms *Streptomyces kitasatoensis* which had been deposited at the Northern Utilization Research and Development Division, U.S. Department of Agriculture, Peoria, Ill., U.S.A., and added to its collection of micro-organisms as NRRL 2,486 and 2,487. The description of the organisms are set forth in the following.

Morphological findings

A mycelium was formed with the display of slightly curved hyphae on Czapek's agar media though development of aerial mycelium was poor.

Cultivating on starch, asparagine or tyrosine agar, thin grayish white aerial mycelia grew after several days, sometimes cottony or flocculous aerial mycelia appeared. In some instances the aerial mycelium grew slowly and sparsely. Later the color of the aerial mycelia on starch or asparagine agar

was changed white to yellow or light tan yellow. Ordinarily the primary and secondary whisks will grow in an amount that ranges from a few to many, however sometimes whisk formation becomes progressively degenerated until none can be detected. Sometimes, few spirals of hyphae were observed. Cultural findings:

5	(1) Czapek's agar:	
	Growth:	yellow to yellowish brown, penetrating into the medium.
25	Aerial mycelia;	none to grayish white.
	Soluble pigment;	none to yellowish.
30	(2) Krainsky's agar:	
	Growth:	yellowish white, center raised, penetrating into the agar, spreading thin edge.
35	Aerial mycelia;	thin, grayish white or yellow.
	Soluble pigment;	none to light yellowish.
40	In the course of incubation small cottony patches which turned from white to light tan yellow appeared and whole surface was covered by them.	
	(3) Nutrient agar:	brown restricting with raised center, folds from center to edge.
45	Growth:	none
	Aerial mycelia;	brown.
50	(4) Glucose agar:	brown to dark brown, penetrating into agar.
	Growth:	very faint, grayish or mouse gray.
55	(5) Starch agar:	brown to yellow or yellowish brown, penetrating into medium, center raised and brown.
	Growth:	thin
60	Aerial mycelia;	In the course of cultivation, white cottony or flocculous aerial mycelia grew rapidly, and the whole surface of the medium was covered soon, and tinged with yellowish color.
	Soluble pigment;	none or slight.
65	(6) Tyrosine agar:	brown to dark brown, penetrating into medium.
	Growth:	grayish white and thin, later cottony.
70	Aerial mycelia;	positive
	Sometimes tyrosinase production was negative in some strains, giving faint yellowish coloring of medium. Otherwise abundant production of grayish black pigment was observed.	
75	(7) Potato plug:	yellowish brown and wrinkled.
	Growth:	none or white, thin, sometimes became cottony and light tan yellowish.
80	Aerial mycelia;	unchanged or light brown or sometimes
	Color of plug;	blackening to show a chromogenic type.
85	(8) Carrot plug:	brown to dark brown.
	Growth:	none or whitish gray.
90	Aerial mycelia;	unchanged.
	Color of plug;	poor, dark brown.
95	(9) Gelatin stab:	slow but completely, about a half of the medium in 20 days, and only a droplet of liquefied portion was observed in some strains.
	Growth:	
100	Liquefaction;	weak or negative.
	Coagulation;	positive.
105	Peptization;	yellow to brownish yellow to dark brown.
	Color of ring;	

(11) Egg medium:	grayish brown.
Growth:	thin, spreading, grayish white, became
Aerial mycelia:	cottony.
Soluble pigment:	purple.
(12) Serum:	brownish yellow.
Growth:	none.
Aerial mycelia:	brown.
Soluble pigment:	
(13) Blood:	dark brown.
Growth:	none
Aerial mycelia:	positive.
Hemolysis:	positive.
(14) Nitrate reduction:	positive.
(15) Starch hydrolysis:	positive.
(16) Cellulose decomposition:	negative.
(17) Hydrogen sulfide production:	positive.
(18) Utilization of carbon sources:	
Utilized:	glucose, starch, dextrin, glycerol, galactose, maltose, trehalose, sucrose, inositol, sorbitol, sodium succinate, sodium citrate, sodium acetate.
Not utilized:	xylose, rhamnose, raffinose, lactose, arabinose, mannose, mannosid, inulin, dulcitol, fructose, salicine, esculin.

Above-described morphological characteristics of *Streptomyces kitasatoensis* were mainly classified into four types of colony form including natural or induced mutant strains, named type A, B, C, D, respectively.

Type B resembles the original type.
Type D shows irregular form.

Thickness of colony:

Aerial mycelium: Type A>Type B>Type C
Type A and C; none
Type B; poor

Color of colony surface:

Type A; yellowish, glistening.
Type B and C; brown.

Diameter of colony:

Type B>Type A
Type C; very small.
Type A; less than three.
Type B; more than three.
Type C; none

The cultivation of the organisms *Streptomyces kitasatoensis* may take place in a variety of liquid culture media. Media which are useful for the production of the novel antibiotic may include an assimilable source of carbon such as lactose, maltose, dextrose, molasses, starch, glucose, corn syrup, sugar, glycerine, fatty acids such as stearic acid, palmitic acid, acetic acid, propionic acid, etc., an assimilable source of organic and inorganic nitrogen such as corn steep liquor, yeast or its extract, meat extract, meat juice, peptone, milk, cottonseed oil, casein hydrolysate, amino acids, soybean powder, etc., and such as inorganic nitrate, ammonium salts and the like. These nitrogen sources are used separately or in combination. This applies to the carbon sources. The aforementioned carbon and nitrogen sources are only illustrative, and thus have been set forth in no limiting sense for the invention. The media further include the source of inorganic anions and cations, such as potassium, sodium, calcium in the form of phosphate, carbonate, chloride, etc. Trace elements such as boron, molybdenum, copper, nickel, cobalt, iron, etc., especially in the form of, for instance, ferro- and ferric chloride, sulfate, those of cupro- and cupric compounds, or the like, may be added to the media.

For the culture of streptomyceteous micro-organisms belonging to *Streptomyces kitasatoensis*, either the liquid culture process or the solid culture process may be employed. For the industrial purpose, however, the submerged aeration culture is most advantageous.

For carrying out the culture of the organisms for the preparation of crude antibiotics according to the invention, the culturing temperature is kept generally at 20°-40° C., preferably 25°-35° C. The culturing period, when the aeration is employed, extends generally to 2-10 days. When the culture broth reveals a highest potency in antibiotic performance, the

culture should naturally be ceased. In order to separate and purify the crude antibiotic products from the broth, various conventional processes commonly employed for this purpose, such as solvent extraction, adsorbent treatment, distribution chromatography, crystallization from solvents, and the like techniques, may be employed.

In order to prepare a solvent extract containing the crude antibiotics, the filtrate of the culture broth of the streptomyceteous organisms, upon removing the mycelia off, is subjected to extraction generally at a pH of 7 to an alkalinity, preferable pH 7.5-9, with use of a water-immiscible organic solvent, such as alcohol, for instance, butanol, propanol or the like; ketone such as methyl ethyl ketone or the like; ester such as ethyl acetate, butyl acetate or the like; chloroform; benzene; xylol; toluol, etc. The extract is mixed with a proper quantity of acidic water of pH 2-4 so as to control the aqueous liquid to pH 2-4, in order to transfer the effective antibiotics to the aqueous phase which is then mixed with a water-immiscible organic solvent while adjusting the pH to 7.5-9.0. This adjustment may be carried out in advance of, in the course of, or, after the mixing step. This transfer operation is repeated several times until sufficiently condensed crude antibiotics are contained in the final organic solvent solution which is then subjected to a distillation in vacuo or a condensing step. In this way, an antibiotic composition which includes A₃, A₄, A₅, A₆, A₇, A₈ and A₉, compounds can be separated. Or alternatively, an addition of petroleum ether, the antibiotics can be sedimented. In a still another way, the final condensed solution containing the effective antibiotics may be subjected to lyophilization for the desired separation of the crude products.

The condensed solution may be alternatively treated so that it is adjusted to pH 7.0-9.0 so as to precipitate the effective antibiotics in the form of their free bases.

35 The thus-obtained products represent the following properties:

Appearances: white powder
Melting point: 128°-145° C.
Elemental analysis: C: 60.00%; H: 8.80%; N: 1.68%, as found.

40 Infrared absorption spectrum (using KBr - tablet, is shown in FIG. 1.

Ultraviolet absorption spectrum:

$\lambda_{\text{methanol}}$, 231 m μ

E_{1 cm.}, 353

45 Molecular weight (by titration): ca. 800

Optical rotation: $[\alpha]_D^{25} = -53^\circ$ (C=1; chloroform).

This antibiotic composition is soluble in lower alcohols such as methanol, ethanol and the like; esters such as ethyl acetate, butyl acetate and the like; ketones such as acetone, methyl isobutyl ketone and the like; benzene; chloroform and the like; difficult to dissolve in water; insoluble in petroleum ether.

50 Color reactions on the new antibiotic composition are as follows:

negative: Adamkiewicz's reaction; biuret reaction: Milon reaction; xanthoprotein reaction.

positive: Anthrone reaction; Schriwanoff's reaction; Molisch's reaction; conc. sulfuric acid reaction; tetrazolium reaction.

55 When it is desired to isolate several constituent antibiotic compounds A₃, A₄, A₅, A₆, A₇, A₈ and A₉, from the said composition, the latter is further treated by the chromatography technique using silica gel, cellulosic material, activated alumina or the like, by the countercurrent distribution technique, or the like.

As an example, the antibiotic composition is adsorbed by a proper quantity of silica gel, activated alumina or the like material which is commonly used in the conventional chromatographic processing and then dissolved in a combination solvent system, for instance, benzene/acetone, benzene/methanol or the like. By further treating the solvent system as conventionally, each of the constituent compounds 60 can be isolated in the form of white prisms, with exception of

A_5 , A_7 and A_9 which are in the form of white crystalline powder.

Infrared absorption spectrum

Those taken with use of carbon tetrachloride solutions are shown in FIGS. 1-7, respectively in the order of A_3 - A_9 compounds.

Nuclear magnetic resonance spectra are shown in FIGS. 8-14, respectively, in the order of A_3 - A_9 compounds.

Solubility

35 The following table I shows respective solubility of the respective compound:

Color reactions of A_3 to A_9 compounds are just same as discussed hereinbefore with respect to the antibiotic composition, as follows:
negative: Adamkiewicz's reaction: biuret reaction: Milon reaction; xanthoprotein reaction.
positive: anthrone reaction: Schriwanoff's reaction; Molisch's reaction; conc. sulfuric acid reaction; tetrazolium reaction.
Proposed formula:
According to our experimental determination, we propose the following general formula covering the aforementioned 60 new antibiotic compounds A_3 - A_9 :

wherein R_1 represents hydrogen and R_2 represents acetyl, propionyl, butyryl; or wherein R_1 represents acetyl and R_2 represents acetyl, propionyl, butyryl and isovaleryl.

A clear understanding may be obtained by reference to the following table II.

TABLE II

Nomination of Compound	Molecular formula	Radical R_1	Radical R_2
A_3	$C_{42}H_{69}NO_{15}$	$-\overset{\parallel}{C}-CH_3$	$-\overset{\parallel}{C}-CH_2-CH$ CH ₃
A_4	$C_{41}H_{67}NO_{15}$	Same	$-\overset{\parallel}{C}-CH_2-CH_2-CH_3$
A_5	$C_{39}H_{65}NO_{14}$	H	Same as above.
A_6	$C_{40}H_{65}NO_{15}$	$-\overset{\parallel}{C}-CH_3$	$-\overset{\parallel}{C}-CH_2-CH_3$
A_7	$C_{38}H_{63}NO_{14}$	H	Same as above.
A_8	$C_{39}H_{63}NO_{15}$	$-\overset{\parallel}{C}-CH_3$	$-\overset{\parallel}{C}-CH_3$
A_9	$C_{37}H_{61}NO_{14}$	H	Same as above.

These properties of A_3 , A_4 , A_5 , A_6 , A_7 , A_8 , and A_9 compounds serve to distinguish those from other known macrolide antibiotics such as spiramycin, carbomycin, erythromycin, methymycin and oleandomycin, because of having different chemical structures.

Of those antibiotics denoted in the prior art, leucomycin A_2 , B_1 , B_2 , B_3 and B_4 are different from the compounds A_3 - A_9 in their physicochemical properties.

Antimicrobial spectra of the novel antibiotic compounds are shown in the following table III.

TABLE III

	A_9 Compound	>500	>1,000

EXAMPLE 1

Preparation of activity in shaker bottles

One hundred milliliters of an aqueous culture medium comprising peptone 0.5%, meat extract 0.5%, glucose 2%, common salt 0.3%, dry yeast 0.3%, and calcium carbonate 0.3% were introduced into a 500-milliliter Sakaguchi flask, adjusted to pH 7, sterilized at 120° C. with steam at 15 p.s.i. for about 60 minutes, inoculated with *Streptomyces kitasatoensis* and then reciprocally shake cultured at 27° C. for 72 hours.

Next, 1 liter of a fermentation medium comprising soybean powder 3%, cone steep liquor 2%, starch 2%, glucose 1%, sodium chloride 0.3%, calcium carbonate 0.5%, potassium phosphate dibasic 0.1%, magnesium sulfate 0.05%, potassium chloride 0.05% and manganese sulfate 0.0003% was equally divided and introduced into 10 Sakaguchi flasks having each a volumetric capacity of 500 milliliters, thus each flask containing 100 milliliters of said medium. After sterilization, 1 milliliter of the incubated and cultured medium in the foregoing stage was transferred to each of said prepared flasks which are then incubated on a reciprocating shaker at 27° C. for 96 hours. The broth gathered from all the flasks contained a mix-

ture of the new antibiotics, or A_3 , A_4 , A_5 , A_6 , A_7 , A_8 and A_9 compounds, 550 mg./ml. when convertedly calculated to the corresponding amount of the normal standardized leu-

mycin. It was then filtered off for removal of the mycelia.

Eight hundred milliliters of the filtrate was adjusted to a pH of 8.5, extracted twice with benzene, 300 milliliters, and the benzene phase was further extracted twice with an aqueous hydrochloric acid, 150 milliliters, of pH 3.5. The aqueous phase was controlled to pH 8.5 and extracted twice with 100 milliliters of benzene. The benzene extract was dehydrated over anhydrous sodium sulfate and dried freezingly. In this way, a mixture of antibiotics A₃ to A₉ was obtained in white powder.

Yield: 400 milligrams.

EXAMPLE 2

The last benzene extract obtained in the foregoing example was further extracted with 50 milliliters of aqueous hydrochloric acid, pH 3, and the aqueous phase was separated off and adjusted to pH 9 so as to cause enough sedimentation of the antibiotics. Other treating conditions and procedures were substantially same as employed in the foregoing example. The antibiotics were in the form of white powder.

Yield: 340 milligrams.

EXAMPLE 3

Large-scale production of antibiotics

An aqueous culture medium comprising peptone 0.5%, meat extract 0.5%, glucose 2%, sodium chloride 0.5%, dry yeast 0.3% and calcium carbonate 0.3%, made up in a volume of 100 milliliters, and introduced into a 500-milliliter Sakaguchi flask, adjusted to pH 7, sterilized as usual manner, inoculated with *Streptomyces kitasatoensis*, and then cultured at 27° C. for 72 hours with reciprocal shaking.

The fermented broth was inoculated under completely aseptic conditions to 20 liters of a fermentation medium comprising soybean powder 3%, starch 2%, glucose 1%, sodium chloride 0.5%, ammonium sulfate 0.3%, dry yeast 0.5%, calcium carbonate 0.3%, potassium phosphate dibasic 0.1% and urea 0.01% and contained in a 30-liter jar fermenter already sterilized.

The fermentation mixture was incubated at 27° C. for 50 hours while agitating by an impeller revolving at 250 revolutions per minute and being forced through with sterile air at a rate of 20 liters per minute.

The broth was then transferred aseptically to a 400-liter stainless steel fermenter tank and mixed evenly with 200 liters of fermentation medium of the same composition as that disclosed above and contained therein.

The mixture in the tank was further incubated at 27° C. for 85 hours while being agitated by an impeller rotating at 200 revolutions per minute and aerated with sterile air at a rate of 200 liters per minute. At the end of the incubation, the broth contained a mixture of the aforementioned seven kinds of antibiotics, 1,200 mg./ml., when convertedly calculated to the corresponding quantity of the normal and standardized leucomycin. One hundred and sixty liters of the filtrate obtained from the broth after centrifuging removal of the mycelia were adjusted to pH 8 and extracted twice with 50 liters of butyl acetate. The separated butyl acetate phase was adjusted to pH 3 by the addition of 30 liters of aqueous hydrochloric acid of pH 3, agitated strongly and the separated aqueous phase was conditioned to pH 8.5, and then extracted twice with 8 liters of butyl acetate. The butyl acetate phase was extracted with 6 liters of aqueous hydrochloric acid of pH 3.5. The aqueous phase, after adjusted to pH 9, was extracted twice with 6 liters of benzene. The benzene phases were collected together and subjected to a condensation under vacuo. In this way, 130 grams of the antibiotic mixture were obtained in the form of white powder free base.

The potency: 1,150 mg./mg.

EXAMPLE 4

Preparation and isolation of compound A₃

Two hundred and fifty milligrams of the white powder 75

product were dissolved in 1 milliliter of benzene and the solution was poured into the top end of a chromatocolumn, having a diameter of 1 centimeter and filled with 10 grams of silica gel in benzene. Then, the column was washed with benzene thoroughly. Next, a benzene/acetone mixture, ratio being 5:1, was led to pass through the column at a flow rate of 1/4 v.v.h. (which means a rate of hourly flow corresponding to a quarter of the quantity of the silica gel). The eluate was dividingly collected in a large number of tubes in the quantity of 1 milliliter per tube, using a fraction collector. Upon investigating the composition of the content of each tube relying upon the thin layer chromatographic method, it was found that the tubes No. 15-25 contained considerable amounts of the compound 15 A₃.

The contents of the above-specified tubes were collected together and the solvent was distilled off under vacuo. The residual was dissolved in benzene at 60° C., and left overnight in a ice-cooled chamber. The crystalline product, compound 20 A₃, was obtained as free base in white prisms.

Yield: 30 milligrams.

EXAMPLE 5

Isolation of Compound A₃

Four grams of the product white powder obtained in example 3 were subjected to a countercurrent distribution using a solvent system of benzene/chloroform/methanol/1/15 molar citric acid buffer, pH 4.9 (mixing ratio by weight - 20:6:20:8), 30 and transferred 300 tubes, each of which collected 10 milliliters of the treated solvent. Upon investigation into the tube contents relying upon the silica gel thin layer chromatography, it was found that the tubes specified as No. 65-80 contained considerably the compound A₃. These tube contents were then collected together and treated as before, so as to isolate the free base of compound which was in the form of white powder.

Yield: 350 milligrams.

Thus-obtained compound A₃ was dissolved in 5 milliliters of ethylether and dropped into 5 milliliters of 2-percent solution of tartaric acid in ethylether with stirring. Precipitated compound A₃ tartrate was washed with ethylether and dried after isolation.

45 Yield: 400 milligrams.

EXAMPLE 6

Isolation of Compound A₄

Among the tubes treated in the foregoing example 4 the contents of those specified as No. 28-35 were collected together and distilled off under vacuo for removal of the solvent. The residual white powder was dissolved in 1 milliliter of benzene and poured into the top end of a chromatocolumn, 6-millimeter diameter, filled with 5 grams of silica gel mixed with a proper quantity of benzene, and then a solvent mixture of benzene and acetone, 4:1, was led to pass through the column as rechromatography. The resultant solvent solution was then distilled off and the residual was recrystallized from hot benzene. The thus obtained crystalline compound A₄ free base was in the form of white prisms.

60 Yield: 20 milligrams.

EXAMPLE 7

Isolation of Compound A₄

The contents of the tubes specified as No. 95-115 in example 5 were collected together and treated in the usual method as before. In this way, the compound A₄ in white powder was obtained.

70 Yield: 294 milligrams.

EXAMPLE 8

Isolation of Compound A₅

The contents of the tubes specified as No. 45-68 in example

4 were collected together and treated by the chromatographic technique (eluted with a solvent mixture of benzene and acetone, 3:1) as before. In this way, the compound A₅ free base in white powder was obtained. Yield 35 milligrams.

EXAMPLE 9

Isolation of Compound A₅

The contents of the tubes specified as No. 171-295 in example 5 were collected together and treated as before. Yield of the compound A₅; 480 milligrams.

EXAMPLE 10

Isolation of the Compound A₆

Two hundred and fifty milligrams of the white powder product obtained in example 3 were dissolved in 1 milliliter of benzene and the solution was poured into the top end of a chromatocolumn, 1 centimeter in diameter and filled with 10 grams of silica gel in benzene, and charged. The charged column was washed by eluting with benzene thoroughly. Next, a benzene/acetone mixture, ratio being 4:1, was led to pass through the column at a flow rate of $\frac{1}{4}$ v.v.hr. (which was explained as before). The eluate was dividingly collected in a large number of tubes in a quantity of 1 milliliter per tube, using a fraction collector.

The contents of the tubes numbered No. 26-40 were collected together and distilled off for removal of the solvent. The residual white powder was dissolved in 1 milliliter of benzene and poured from the top end of a chromatocolumn, 6 millimeters in diameter, filled with 5 grams of activated alumina mixed with a suitable quantity of benzene. Then, a solvent mixture of benzene/ethyl acetate (2:3) was led to pass through the column as a second chromatographic stage. The effluent was distilled off in vacuo and the residue was recrystallized from hot benzene. The product was obtained in white prisms and the yield of the compound A₆ free base amounted to 15 milligrams.

EXAMPLE 11

Isolation of Compound A₆

Thirty-five grams of the white powder product obtained in example 3 were dissolved in 70 milliliters of benzene, and the solution was poured into the top end of a chromatocolumn, 10 centimeters in diameter and filled with 900 grams of silica gel in benzene, and charged. The charged column was washed with benzene thoroughly. Then, a benzene/acetone mixture, ratio being 4:1, was led to pass through the column at a flow rate of $\frac{1}{4}$ v.v.hr. The eluate was collected each 20 milliliters using a fraction collector.

The contents of the tubes numbered No. 130-170 were collected together and distilled off the solvent in vacuo. The residual white powder was dissolved in 20 milliliters of benzene and then poured into the top end of a second chromatocolumn, of 3 centimeters in diameter, filled with 100 grams of activated alumina mixed with a proper quantity of benzene. Then, a solvent mixture, benzene/ethyl acetate (2:3) was led to pass the column. The eluate was collected, distilled off in vacuo and recrystallized from hot benzene. The thus purified product or the compound A₆ was in the form of white crystals. Yield: 800 milligrams.

EXAMPLE 12

Isolation of the Compound A₇

Two hundred and fifty milligrams of the white powder product obtained in example 3 were dissolved in 1 milliliter of benzene, and the solution was poured into the top end of a chromatocolumn, 1 centimeter in diameter and filled with 10 grams of silica gel in benzene, and charged. The charged column was washed with benzene. Next, a benzene/acetone mixture, ratio being 3:1, was led to pass through the column at

a flow rate of $\frac{1}{4}$ v.v.hr. The eluent was collected each 1 milliliter using a fraction collector.

The contents of the tubes specified as No. 35-55 were collected together and distilled off the solvent in vacuo, and the obtained residue in white powder was dissolved in a small quantity of benzene and subjected to a second chromatographic treatment as before. In this way, the compound A₇ in the form of crystalline white powder was isolated. Yield: 10 milligrams.

EXAMPLE 13

Isolation of Compound A₇

The contents in the tubes specified as No. 220-245 in the example 5 were collected together and subjected to further treatment as before. A crude white powder 200 mg. of the compound A₇ was obtained. This crude product was treated further chromatographically in the substantially same manner as in the case of the foregoing example 12. In this way, the compound A₇ free base was isolated in the form of white crystalline powder. Yield: 100 milligrams.

EXAMPLE 14

Isolation of Compound A₈

The contents of the tubes specified as No. 30-40 in the first half of example 12 were collected together and distilled off the solvent in vacuo, and the obtained white powder was dissolved in a small quantity of benzene and subjected to aforementioned chromatographic treatment. In this way, the compound A₈ free base in the form of white crystal was isolated. Yield: 5 milligrams.

EXAMPLE 15

Isolation of Compound A₈

Thirty-five grams of white powder obtained in the example 3 were dissolved in 70 milliliters of benzene, and the solution was poured into the top of the chromatographic column of 6 centimeters in diameter, filled with 700 grams of activated alumina in benzene, and charged. After washing with benzene, a mixture of benzene and ethyl acetate (1:2 in ratio) was led to pass through the column at a flow rate of $\frac{1}{4}$ v.v.hr. The eluate was collected each 20 milliliters individually. Each contents of the tubes were checked by a method of thin layer chromatography. Compound A₈ was confirmed to contain in tubes Nos. 13-40. The contents of these tubes were collected together and distilled off in vacuo. The residue was dissolved in 30 milliliters of benzene and then poured into the top of a chromatographic column, of 5 centimeters in diameter, filled with a mixture of 375 grams of silica gel and suitable volume of benzene. Then, eluted with a solvent system of benzene/acetone (3:1) and the contents of the tubes Nos. 150-170 were collected together and dried up in vacuo. The obtained residue was recrystallized from hot benzene. Compound A₈ was obtained in the form of white needle crystals. Yield: 500 milligrams.

EXAMPLE 16

Isolation of Compound A₉

The contents of the tubes specified as No. 60-70 in the first half of example 12 were collected together and dried up in vacuo, and the thus-obtained white powder was dissolved in benzene and treated by aforementioned rechromatographic method. Then, the compound A₉ free base was isolated in the form of white crystalline powder. Yield: 20 milligrams.

EXAMPLE 17

Isolation of Compound A₉

Thirty-five grams of white powder obtained in the example 3 were dissolved in 70 milliliters of benzene. The solution was charged at the top of the chromatographic column, of 6 cen-

timeters in diameter, filled with a mixture of 700 grams of activated alumina and benzene. After the filled column was washed with benzene, a mixture of benzene and ethyl acetate (1:2 in ratio) was led to pass through the column at a flow rate of $\frac{1}{4}$ v.v.hr. The eluate was collected each 20 milliliters dividingly, and the contents were checked by a method of thin layer chromatography using activated alumina. Contents of the tubes from No. 60 to No. 80 were confirmed to be the compound A₉. These were collected together and dried up in vacuo, and then, residue was dissolved in 30 milliliters of benzene. The solution was charged into the top of chromatographic column, of 5 centimeters in diameter, filled with a mixture of 350 grams of silica gel and benzene. Next, eluted with a solvent system of benzene/aceton (3:1), the contents of the tubes Nos. 50-170 were collected together, and then dried up in vacuo. Thus isolated white powder was recrystallized from hot benzene. Compound A₉ was obtained in the form of white crystalline powder.

Yield: 700 milligrams.

We claim:

1. A process for the production of an antibiotic of the formula:

wherein R₁ is hydrogen and R₂ is acetyl, propionyl or butyryl; or wherein R₁ is acetyl and R₂ is acetyl, propionyl, butyryl or isovaleryl, which comprises cultivating a micro-organism belonging to *Streptomyces. kitasatoensis* in an aqueous nutrient medium containing an assimilable source of carbon and nitrogen and essential inorganic cations and anions until substantial antibiotic activity is imparted to said medium, recovering from the broth, the mixture of antibiotics wherein R₁ and R₂ are as defined above and fractionating the mixture to recover said antibiotics.

2. The process according to claim 1 wherein said micro-organism is cultivated under submerged aerobic conditions.

3. The process according to claim 1 wherein the culture broth is extracted at pH 7-9 using a water-immiscible organic solvent, the extract is acidified to pH 2-4, whereby the an-

tibiotic mixture is in the aqueous layer, the aqueous layer adjusted to pH 7.5-9, extracted with a water-immiscible organic solvent and said alternate acidification and basification followed by extraction with said water-immiscible organic solvent, are repeated until the mixture of antibiotics in the form of their bases, is effectively concentrated in the water-immiscible organic solvent.

4. The process according to claim 3 wherein the solvent extract containing the concentrate of said antibiotics is freed of the solvent and lyophilized.

5. The process according to claim 3 wherein said solvent extract containing the mixture of antibiotics is mixed with petroleum ether whereby the mixture of antibiotics precipitates.

6. A process for the production of an antibiotic of the formula as described in claim 1 which comprises cultivating a micro-organism belonging to *Streptomyces. kitasatoensis* in an aqueous nutrient medium at 25-35° C. for 2-10 days under aerobic condition containing an assimilable source of carbon and nitrogen and essential inorganic cations and anions until substantial antibiotic activity is imparted to said medium, recovering the mixture of antibiotics wherein R₁ and R₂ are as

defined therein from the broth, and fractionating the mixture to recover the said antibiotic.

7. The process according to claim 6 wherein the culture broth is extracted at pH 7-9 using a water-immiscible organic solvent, the extract is acidified to pH 2-4, whereby the antibiotic mixture is in the aqueous layer, the aqueous layer adjusted to pH 7.5-9, extracted with a water-immiscible organic solvent and said alternate acidification and basification followed by extraction with said water-immiscible organic solvent, are repeated until the mixture of antibiotics in the form of their bases, is effectively concentrated in the water-immiscible organic solvent.

8. The process according to claim 7 wherein said solvent extract containing the mixture of antibiotics is fractionated by silica gel partition chromatography.
